W. SCHUTTLER

LOCOMOTIVE ARCH

Filed Nov. 20, 1922

Patented Feb. 10, 1925.

UNITED STATES PATENT OFFICE.

WILLIAM SCHUTTLER, OF CHICAGO, ILLINOIS, ASSIGNOR TO UNIVERSAL ARCH COMPANY, OF CHICAGO, ILLINOIS, A CORPORATION OF ILLINOIS.

LOCOMOTIVE ARCH.

Application filed November 20, 1922. Serial No. 602,016.

To all whom it may concern:

Be it known that I, WILLIAM SCHUTTLER, a citizen of the United States, and a resident of Chicago, in the county of Cook and State of Illinois, have invented certain new and useful Improvements in a Locomotive Arch, of which the following is a specification.

My invention relates to locomotive arches and particularly to a novel form of brick construction adapted for use in forming the transverse baffle or wall interposed in a locomotive fire box for the purpose of deflecting the products of combustion. A detail of the construction herein disclosed was first illustrated in my Patent No. 1,420,764, of June 27, 1922.

One of the objects of my invention is to provide a construction in which the inclined side bricks shall be so supported that no transverse bending strain shall be exerted on the side tubes. In the use of arches including an inclined side brick it is not unusual for the side bricks to be installed at such an angle that the continued jar and hammering, due to the passing of the engine over joints, causes the side bricks to wedge in the space between the outside tube and the side sheet and to bend the tube. In the construction here proposed this difficulty is obviated. The side bricks are supported directly on one of the horizontal bricks and the thrust is distributed over all the tubes. By providing on each end of the horizontal bricks and on the larger end of the side brick a hemispherical recess and protuberance, the bricks are made interchangeable and are suitably interlocked without weakening the bricks. This form of interlock has another advantage in that it is so arranged that the workman cannot place or rest the side brick on the outside tube but must place it in its proper position in engagement with the horizontal brick.

The invention will be more readily understood by reference to the accompanying drawings, in which,—

Fig. 1 is an end view of a common form of arch constructed in accordance with my invention;

Fig. 2 is a similar view showing a slightly modified form;

Fig. 3 is a top plan view of one of the horizontal bricks, and

Fig. 4 is a bottom plan view of a side brick.

In the drawings, referring particularly to Figs. 1, 3 and 4, it will be seen that the improvement is shown as applied to a fire box having side sheets 10, and four arch tubes 11. On the tubes are placed bricks 12, the ends of the bricks being grooved to fit on the tubes and the lower surfaces being recessed as indicated at 13. On each end of the middle bricks 12, I provide a hemispherical projection or protuberance 14, and a hemispherical recess 15. These are staggered on opposite ends as indicated in Fig. 1, the brick thus being reversible.

The side bricks 16 are of thinner construction and may likewise be provided with recesses 17 on their lower surfaces. The outer ends 18 are shaped to fit the side sheets 10, and the inner end 19 rests against the inclined portion 20 of the horizontal brick. The end 19 of the side brick is not exactly square but is slightly curved, as shown, in order to permit certain freedom of movement of the side brick to correspond to necessary variations in the space between the side sheet and the outer tube.

In the construction shown in Fig. 2, the bricks 12 and 16 are the same as those just described. However, in this instance the intermediate tubes 21 are more widely spaced and two bricks 22, 23, are employed for bridging the space, these bricks being each of arcuate form and when joined constitute a flat arch. The abutting ends of the two bricks are similarly provided with a hemispherical recess and projection. To this extent the construction is similar to that shown in my patent heretofore referred to. However, in that patent the ends of the bricks are rested on the tubes, whereas in this case the bricks are rested on the ends of adjacent bricks.

It will be noted that the middle bricks 12 are of arcuate form. This construction provides several advantages, one of the most important of which is that of stability even though the brick may be broken transversely. The arched shape of the brick will insure the maintenance of the brick in

position even under the circumstances mentioned.

A construction such as described adapts itself to all the requirements of removal and replacement and may be cheaply manufactured. The form of the interlocking device is such that the bricks may be handled without danger of breaking off the projections. Obviously the construction is capable of adaptations other than those shown and I do not wish to be limited except as indicated in the appended claims.

I claim:

1. The combination with the side sheets and tubes of a locomotive, of a baffle wall comprising middle bricks and side bricks, the middle bricks supported on and fitting between the tubes and the side bricks leaning against the side sheet and supported on the end of a middle brick, the cooperating surfaces of the side and middle bricks being provided with cooperating hemispherical recesses and projections, one of said cooperating surfaces being rounded to permit of limited freedom of movement of the side bricks to accommodate itself to the side sheet, said middle bricks being of arcuate form and having recesses on their under surfaces to lessen the weight thereof.

middle bricks being of duplicate construction, whereby either end may cooperate 25 with a side brick.

2. The combination with the side sheets and tubes of a locomotive, of a baffle wall comprising middle bricks and side bricks, the middle bricks supported on and fitting 30 between the tubes and the side bricks leaning against the side sheet and supported on the end of a middle brick, the cooperating surfaces of the side and middle bricks being provided with cooperating hemispherical recesses and projections, one of said 35 cooperating surfaces being rounded to permit of limited freedom of movement of the side bricks to accommodate itself to the side sheet, said middle bricks being of arcuate 40 form and having recesses on their under surfaces to lessen the weight thereof.

Signed at Chicago, Illinois, this 17th day of November, 1922.

WILLIAM SCHUTTLER.
